(57) **CLAIM**

The ornamental design for an apparatus for generating, distributing or converting electrical energy, as shown and described.

DESCRIPTION

FIG. 1 is a front elevation view of an apparatus for generating, distributing or converting electrical energy;

FIG. 2 is a rear elevation view thereof;

FIG. 3 is a top plan view thereof;

FIG. 4 is a bottom plan view thereof;

FIG. 5 is a left side elevation view thereof;

FIG. 6 is a top perspective view thereof;

FIG. 7 is a bottom perspective view thereof;

FIG. 8 is a top perspective view thereof, with the top cover removed; and,

FIG. 9 is a top plan view thereof, with the top cover removed.

The broken lines shown are included for the purpose of illustrating environmental features and form no part of the claimed design.

UNITED STATES PATENT AND TRADEMARK OFFICE
CERTIFICATE OF CORRECTION

PATENT NO. : Des. 619,960 S
APPLICATION NO. : 29/311155
DATED : July 20, 2010
INVENTOR(S) : Gerald Winkler

Page 1 of 1

It is certified that error appears in the above-identified patent and that said Letters Patent is hereby corrected as shown below:

On the Title Page, Item (73)

The correct spelling should read as follows:

“Truma Geraetetechnik” not --Truma Gereatetechnik--

Signed and Sealed this

Fifth Day of October, 2010

David J. Kappos
